BATTERY LIFTER AND CARRIER

Harry Clyde Roberts, Long Beach, Calif.

Application February 19, 1952, Serial No. 272,427

3 Claims. (Cl. 294—104)

This invention relates to a device primarily for use in lifting storage batteries out of their cradles under the hood of motor vehicles and for carrying the batteries back and forth for servicing or replacement thereof.

It is the object of the present invention to provide a battery lifting and carrying device for attachment to the terminal posts of batteries; a device which will grip the posts without danger of slipping and without damaging the contacted surfaces of the posts. A further object is to provide a battery lifting and carrying device adapted for use on batteries the terminal posts of which are placed different distances apart.

Other objects of the invention, as well as the many advantageous features thereof, will be apparent upon perusal of the following detailed description and by referring to the accompanying drawing in which a preferred form of the invention is illustrated.

In the drawing:

Fig. 1 is a side elevational view of the device of the invention as it appears when placed in position on the terminal posts of a storage battery;

Fig. 2 shows the device as it may be readjusted for use on batteries the terminal posts of which are placed a much greater distance apart;

Fig. 3 is a bottom view of one of the elements of the post gripping member of the invention;

Fig. 4 is a side elevational view of this element with a portion thereof broken away for the sake of clearance; and

Fig. 5 is a plan view of the other element of the post gripping member.

The battery lifter and carrier, in the form illustrated in the drawing, includes a handle 1, from the ends of which extend straps 2, 3 to the gripping members 4. This handle should be long enough to obtain a good grip thereon with both hands, if or when necessary, and the straps are made from suitable, wear resistant, current insulating material.

The gripping member 4 consists of upper and lower elements 5 and 6, which are pivotally combined to grip the terminal post A of a battery B. The upper element 5 is for this purpose made with a pair of studs 7, 8 projecting from the underside thereof and these studs are freely seated in perforations 9, 10 of the lower element 6. The ends of the studs are thereupon spun, hammered or kneaded into the shape substantially as indicated in Fig. 2 to form heads 11 large enough to resist the pressure they are subjected to during the operation of the device. The lower element 6 is shown perforated to provide an opening 12 of a size snugly to seat on the terminal post A when the gripping member of the device is applied thereto. Similar studs 19, 20, 21 project from the element 5 for riveting the straps in position thereon and side flanges 22, 23 are provided better to maintain the straps in position thereon.

The proportions and shapes of these two gripping elements are very important. A portion of the upper element 5 is shown thickened to provide a downwardly extending transverse, substantially semi-circular ridge or flange 15 from the underside of which the studs 7, 8 project. The purpose of this flange is to hold the front edge 16 of the upper element a distance above the upper surface of the lower element at the time the member is placed in position on the post A. It is furthermore important to note that a circular recess 17 is sunk into the front edge of the upper element of a size at the same time snugly to engage the side surface of the post.

When the two elements are so shaped and proportioned, it is found that the upper element will rock on the lower element when the handle is gripped and raised to lift the battery, causing the edge of the recess 17 to swing forwardly against and downwardly along the surface of the post thereby to draw the inner edge of the lower element perforation against the opposite side surface of the post. It is important to note that because

2

the distance between the studs 7, 8 and the edge of the recess 17 is so much shorter than the distance from the studs to the upper end of the element, a very powerful leverage is obtained; also that the pressure against the terminal post increases at the same rate that the force of the pull necessary to lift the battery is increased. All danger of the gripping member slipping on the post is thereby eliminated.

It is seen from the foregoing description that I have provided a very simple and inexpensive battery lifting and carrying device which, by a mere reversal of the device and bending and extending the straps outwardly or inwardly is adapted for convenient use on batteries the terminal posts of which are relatively close together or very far apart.

But while I have herein described a preferred form of the invention, it is to be understood that modifications within the scope of the claims hereto appended may be made without departing from the spirit of the invention.

It may, for example, in some cases be preferred to leave out the rigid handle 1 and to substitute a single strap of the proper length.

I claim:

1. A lifting device attachable to the terminal posts of a storage battery, said device comprising, a strap, an upper gripping element secured to each end of said strap, said element having a transverse rib rising from the lower surface thereof, the outer edge of the element being recessed fittingly to engage the surface of the post, and a lower gripping element having a passage therethrough of a size fittingly to encompass the battery post, the upper element having studs projecting from the rib thereof engaging perforations through the upper surface of the lower element to combine the two elements for relative rocking movement, upward pull on the strap causing the upper gripping elements to rock on their ribs thereby to cause the recessed edges thereof to swing downwardly on the posts to lock the elements rigidly in position on the post.
2. A lifting device attachable to the terminal posts of a storage battery, said device comprising a handle, a strap extending from each end of the handle, an upper gripping element secured to the outer end of each strap, said element having a transverse rib rising from the lower surface thereof, the outer edge of the element being recessed fittingly to engage the surface of the post, and a lower gripping element having a passage therethrough of a size fittingly to encompass the battery post, the upper element having studs projecting from the rib thereof engaging perforations through the upper surface of the lower element to combine the two elements for relative rocking movement, upward pull on the strap causing the upper gripping elements to rock on their ribs thereby to cause the recessed edges thereof to swing downwardly on the posts to lock the elements rigidly in position on the post.
3. A lifting device attachable to the terminal posts of a storage battery, said device comprising, a handle, a strap extending from each end of the handle, an upper gripping element secured to the outer end of each strap, said element having a transverse rib rising from the underside thereof and a pair of studs projecting from said rib, the element having a circular recess sunk into the outer edge thereof for engagement with the surface of the post, and a lower gripping element having transversely aligned perforations therethrough freely engaging said studs, the ends of the studs being upset to form heads pivotally combining the two elements, the lower element having a passage therethrough of a size fittingly to encompass the post of the battery, upward pull on the strap causing the upper gripping elements to rock on their ribs thereby to cause the recessed edges thereof to swing downwardly on the posts tightly to lock the elements in position thereon.
